ADJUSTING HARDWARE FOR SASHES
AND THE LIKE

Sern Madsen, Clinton, Iowa, assignor to George L. Curtis, Eugene J. Curtis, and Charles A. Armstrong, Clinton, Iowa

Application April 16, 1934, Serial No. 720,828

10 Claims. (Cl. 268—117)

The object of my invention is to provide adjusting hardware for sashes and the like, which is simple, durable and comparatively inexpensive to manufacture, the present application being a continuation in part of my copending application Serial No. 693,775, filed October 16th, 1933.

A further object is to provide adjusting hardware including a flexible chain which can bend to some extent in one direction, but which is limited against bending in the other direction so that one end of it can be connected with the sash and the other end can extend into the window frame, with the weight of the chain intermediate the sash and frame tending to maintain the chain in a rigid straight position so that operator mechanism can coact with it and either push or pull it for opening or closing the sash, as desired.

Another object is to provide a chain of this character so that the part of it which at any time is not extended from the window frame to the sash, can be changed in direction and thereby be concealed in a perpendicular recess in the window frame.

Another object is to provide a connector for connecting the outer end of the chain-like element with the sash in such manner as to hold the outer link of the chain against bending in either direction, so as to thereby retain the portion of the chain intermediate the sash and the frame in rigid position for either thrusting or pulling even though the weight of the chain is not operable to retain it straight.

Still a further object is to provide an actuator for moving the chain longitudinally, which actuator is readily operable by means extending from the inside surface of the window frame.

A further object is to provide actuators for the chain in the form of a worm or a sprocket coacting therewith, whereby rotation of the worm or sprocket will actuate the chain to impart longitudinal movement thereto, means also being provided, if desired, to lock the chain in any position to which it is adjusted.

Another object is to provide a form of construction in which the operator is pivoted to the window frame to accommodate a sash hinged in the ordinary manner.

Another object is to provide a novel type of chain adapted to flex in one direction and formed of a plurality of links, each link comprising a sheet metal blank bent to a channel shape, the web of which has a slot for the tooth of a worm to engage and the flanges of which are perforated

for pivot pins used when assembling successive links of the chain together.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of an operator having in it a chain-like element, one half of the casing being removed and parts being broken away and shown in section to clearly illustrate the invention.

Figure 2 is a sectional view on the line 2—2 of Figure 1 showing a locking means.

Figure 3 is a sectional view on the line 3—3 of Figure 1 showing the coaction of the chain with the tooth of a worm gear.

Figure 4 is a horizontal sectional view through a window frame and sash showing my adjusting hardware applied thereto.

Figure 5 is a sectional view as taken on the line 5—5 of Figure 4 and shows the operator in side elevation as well as showing it in its relation to the window frame.

Figure 6 is a sectional view similar to Figure 4 showing a hinged operator instead of a flush mounted type as illustrated in Figure 5 and showing the sash hinged in the ordinary manner instead of by the special supporting hardware of Figure 1, which is more fully disclosed in my copending application hereinbefore mentioned.

Figure 7 is a vertical sectional view through a window frame showing still another modified form of construction.

Figure 8 is an enlarged sectional view on the line 8—8 of Figure 7.

Figure 9 is a view similar to Figure 1 showing an improved type of adjusting hardware.

Figure 10 is a sectional view on the line 10—10 of Figure 9 showing a locking means for the adjusting hardware.

Figure 11 is a sectional view on the line 11—11 of Figure 9 showing the relationship of the operator with the window frame.

Figure 12 is a sectional view through the edge of a sash showing one end of the flexible chain-like element coacting therewith.

Figure 13 is a perspective view of one of the links illustrated in Figure 9.

Figure 14 is a layout view of one of the sheet metal blanks used for the link of Figure 13; and

Figure 15 is a sectional view on the line 15—15 of Figure 9.

Referring to Figure 4, a window frame is illustrated having side jambs 10 and a sill 12. The sill 12 has a stop shoulder 18, while the side jambs 10 have side stops 22. Casings 26 are provided in the ordinary manner. The inside of the window frame may be trimmed in any appropriate manner as by side casings 28 and a stool 32.

To the side jambs 10, screen stops 36 and inside stops 38 are applied.

A sash A is provided and may be mounted in any manner. Preferably it is mounted as shown in my copending application so that one edge thereof travels in a straight line at right angles to the plane of the window frame. This can be accomplished by means of brackets 54 having rollers 62 adapted to coast with tracks 60 and link connections including links 68. The links 68 are pivoted at one end to the window frame and at the other end to the sash A adjacent the center thereof.

During the opening movement of the sash, its center will be guided outwardly, while its left edge will be guided by the rollers 62 and the track 60. The resultant motion of the opening or right hand edge of the sash due to being guided by the hinge arm 68 and the track 60, will be substantially a straight line outwardly perpendicular to the plane of the window frame and in line with the inner face of the right hand side jamb. It is important that the hinge mechanism provide a straight line motion for this edge of the sash since my preferred form of operating mechanism must operate substantially in a straight line motion and in the path just described.

I provide an operator B, shown in Figures 1 to 5 inclusive, for swinging the sash A outwardly and holding it in any desired position to which it is swung. The operator B includes a split housing 76, a flexible chain-like element 78 and a worm 80. The housing 76 is illustrated applied to the right hand side jamb 10 and mounted flush with the stops 38 which extend from the sill 12 to the housing 76, thus placing the housing 76 in a countersunk position with its face flush with the faces of the stops 38. The two parts of the split housing 76 are held together by screws 82 which at the same time anchor the casing to the side jambs.

Within the housing 76, a pair of guides 84 is provided which guide the chain-like element 78 over a ninety degree bend. Thus one end of the chain 78 can extend horizontally outward to the sash A, while the other end can hang vertically downward, the lower stop 38 having a groove 86 to receive and conceal the down hanging end of the chain.

The chain 78 is of peculiar construction. It comprises ordinary chain links 88 and 90 with the addition of anti-back bend links 92. These permit the chain to flex or bend in one direction as around the curved part of the lower guide 84 in Figure 3, but prevent it from bending between the housing 76 and the sash A.

The outer end of the chain 78 is provided with a bracket 94 associated with the outer link 92 to prevent the chain from bending up or down and it is allowed pivotal movement horizontally by a vertical pin 96 mounted in a bracket 98 secured to the sash A. The vertical pivot pin 96 permits swinging of the sash A relative to the chain 78 during the adjusting of the sash.

Each of the links 92 is provided with a groove 100 in the back thereof with which teeth 102 of

the worm 80 coast. It is therefore obvious that rotation of the worm will cause longitudinal movement of the chain 78 relative to the guide 84 in the housing 76.

The worm 80 has reduced ends 104 journalled in the housing 76 whereby it may be supported rotatably relative thereto and a crank 106 is associated (detachably if desired) with the worm 80 to rotate it for adjusting the sash relative to the window frame. I have shown the crank 106 10 as having a slot 108 detachably coacting with a pin 110 in a socket 112 of the worm into which the shank of the crank extends.

If the pitch of the teeth 102 is too great to prevent the worm from holding the chain 78 against movement after once being adjusted, a lock can be provided, which in Figures 1 and 2 I have illustrated as a form of brake band 114 normally loose enough to permit rotation of the worm 80, but being tightenable therearound by 20 screwing a lock screw 116 inwardly.

It will be noted that both sides of the housing 76 are threaded, as at 118, and the brake band 114 is symmetrical so that the housing 76 can be used either on the right or left hand side of 25 the window frame.

Adjustment of the sash A from the foregoing description will be readily apparent. The lock screw 116 is first loosened and then the crank 106 can be rotated in either direction (clockwise to 30 close the window and counterclockwise to open it).

During the rotation of the worm 80, the chain 78 will be retracted or expelled into or from the left hand side of the housing 76 in Figure 1, while the inner end of the chain will be retracted from the bottom of the casing and at the same time move longitudinally of the groove 86 in the stop 38. The screen stop 36 is provided with a notch 120 (see Figure 5) for the chain 78 40 to extend through. The screen stop conceals this part of the chain and the chain can be adjusted from the inside of the window frame without removing or otherwise disturbing the screen.

With the parts of the adjusting hardware being concealed as already described, a neat appearance is given to the entire assembly and thus is eliminated the unattractive usual types of casement window hardware.

In Figure 6, I show how a sash A can be 50 hinged at 134 in the ordinary manner and an operator B can be hinged, as at 136, so as to swing and thereby permit the right edge of the sash to swing on an arc rather than travel in a straight line.

In Figure 7, I show how the worm 80 can be dispensed with. A housing 16c is provided which serves merely as a guide for guiding a chain 78c through a quarter turn. The depending end of the chain is provided with an operating handle 60 158 extending through a slotted plate 169 on a stop 38c. In addition to this, any suitable means can be provided for locking the chain in any adjusted position.

It will be noted that I have located the adjusting hardware substantially midway between the top and bottom of the window frame. This is the most advantageous position for it as any wind pressure against the sash is thereby balanced instead of being greater above or below the adjustor hardware when it is mounted at the top or bottom of the window. The position I illustrate is the point of greatest mechanical advantage.

In Figures 9 to 15 inclusive, I have shown an 75

improved type of adjustor hardware. It consists of a split casing 170 having a chain C of sheet metal construction. The links of the chain C are made of blanks shown in Figure 14 having slots 172 in their webs and perforations 174 in their flanges.

The slots are for a tooth 176 of a worm 178, while the perforations are for pivot pins 180. The blank shown in Figure 14 is formed to the shape illustrated in Figure 13 by bending at right angles on the lines 182 and at slight angles on the lines 184. This makes the link channel-shaped and provides the flanges at one end spaced closer together than at the other end so that the flanges at the first end can fit between the second flanges of the next link. The ends of the webs, as indicated at 186, serve as shoulders to engage each other to prevent flexion of the chain in one direction, although the chain is permitted to flex in the opposite direction.

Some parts of Figures 9 to 15 are similar to parts of Figures 1 to 5. These parts are given the same reference numerals with the addition of the distinguishing characteristic *a*. Instead of the brake band-like friction device 114, friction blocks 188 can be provided for engaging opposite sides of a sleeve 190 which extends from the worm 178. Screws 192 and 194 are illustrated for adjusting these blocks toward each other for thus increasing their friction on the sleeve 190. The screws 192 and 194 may be ordinary countersunk head screws or one of them may be knurled as shown in Figure 10 for convenience in adjusting the friction blocks.

The end of the chain attached to the sash A is illustrated in Figure 12. The means of attachment comprises a countersunk bracket 196 having a vertical pin 198 to which is pivoted a block 200 for pivotal connection with the end of the chain.

In Figure 15, I have shown the guide means for the chain C. It consists of top and bottom walls 202 and 204 and side walls 206. The ends of this wall assembly are confined in openings 208 of the casing 170, while the intermediate portions thereof are provided with extensions 210 shouldered, extended through openings in the side of the casing 170 and riveted as indicated at 212. The side walls 206 are provided with longitudinally arranged grooves 214 to accommodate the riveted ends of the pivot pins 180 of the chain C.

The casing 170 is preferably provided with shoulders 216. These are aligned with screen stop shoulders 218 of side jamb stop strips 220, the lower one having a groove 219 similar to the groove 86 in the stop 38 for receiving the chain. Thus the enlarged part of the casing 170 for accommodating the worm 178 forms a continuation of a portion of the strip 220, making a neater looking flush mounted operator casing.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:—

1. In a structure of the kind described, a frame, a stop strip projecting from the face thereof, a closure member for said frame and movable relative thereto, an operator on said frame, a casing therefor and a flexible chain-like member attached at one end to said closure member and

passing through said casing, said operator coacting therewith to retract and expel said chain-like member upon movement of said operator, said casing being symmetrical in structure to facilitate right or left hand application, each of the two opposite faces thereof being formed with a projection to align with said stop strip on the face of the frame member and form a continuation thereof so said casing may be mortised into said frame to form a smooth surface flush therewith and with said stop strip.

2. In a structure of the kind described, a frame member and a closure member relatively movable, an operator on said frame member, a casing therefor, a flexible chain-like element coacting with said operator and with said closure member, said chain-like element being adapted to deflect in one direction only, means within said casing for causing deflection thereof, said chain-like element comprising a series of links, each link comprising a channel-shaped element having a diagonal slot in its web, extending the full width thereof and partially into the flanges of said channel-shaped element and pivot pins coacting with the flanges of the successive channel-shaped elements, said operator including a worm, a tooth of which engages the slots of said webs and flanges.

3. In a structure of the kind described, a frame member and a closure member relatively movable, an operator on said frame member, a casing therefor, a flexible chain-like element coacting with said operator and with said closure member, said chain-like element being adapted to deflect in one direction only, means within said casing for causing deflection thereof, said chain-like element comprising a series of links, each link comprising a sheet metal blank bent to form a central web and flanges on each side thereof, said web being slotted throughout its width with the terminal ends of the slots located in said flanges and said flanges being perforated and pivot pins through the perforations of the successive links, said operator including a worm, a tooth of which engages the slots of said webs and flanges.

4. In a structure of the kind described, a frame member and a closure member relatively movable, an operator on said frame member, a casing therefor, a flexible chain-like element coacting with said operator and with said closure member, said chain-like element being adapted to deflect in one direction only, means within said casing for causing deflection thereof, said chain-like element comprising a series of links, pivot pins for pivoting successive links together and guide means within said operator for said links, said guide means comprising curved top and bottom walls and a pair of side walls for engaging the sides of said links, said side walls having longitudinally arranged grooves to accommodate the ends of said pivot pins.

5. In a structure of the kind described, a frame, a closure member therefor and movable relative thereto, an operator on said frame, a casing therefor, a flexible chain-like member attached at one end to said closure member and passing through said casing, said operator including a worm gear coacting with said chain-like member to retract and expel it upon rotation of the worm gear and means for locking said worm gear against rotation comprising a pair of friction blocks and clamping means for adjusting them toward opposite sides of said worm gear.

6. In a structure of the kind described, a frame, a closure member for said frame and movable relative thereto, an operator on said frame, a casing

therefor, a flexible chain-like member attached at one end to said closure member and passing through said casing and a screen stop on said frame, said casing having a shoulder in alignment 5 with a stop shoulder of said screen stop and being flush mounted with and of the same contour as the inner face of said screen stop.

7. In a structure of the kind described, a frame member and a closure member relatively movable, 10 an operator on said frame member, a casing therefor, a flexible chain-like element coacting with said closure member, said chain-like element being adapted to deflect in one direction only, means within said casing for causing such deflection 15 thereof, said chain-like element comprising a series of links, pivot pins for pivoting successive links together and guide means within said casing for said link, said guide means comprising curved top and bottom walls and a pair of side walls for 20 engaging the sides of said links, said top and bottom walls being supported by said side walls.

8. In a structure of the kind described, a frame and an out swinging sash therefor, a chain member coacting with said frame and said sash, and 25 an operator for said chain fixed to one side of said frame, a casing for said operator, a rigid 90 degree guide channel therethrough, a manually operated worm rotatably supported by said casing, said chain being bendable from an extended 30 linear position in one direction only, a pivot hinge on said sash, said chain being connected thereto, slideable and bendable through said guide and actuated by said worm, angular slots in the links of said chain for mesh with the teeth of said 35 worm, whereby movement of said chain effects relative adjustment between the frame and sash, in relation to the specifically mentioned side of said frame, both the axis of said sash and the axis of said pivot hinge being parallel to the axis of swing of said sash and the axes of the chain links being at right angles thereto.

9. In a structure of the kind described, a frame and an out swinging sash therefor, a chain mem- 40

ber coacting with said frame and said sash, and an operator for said chain fixed to one side of said frame, a casing for said operator, a rigid 90 degree guide channel therethrough, a manually operated worm rotatably supported by said casing, 5 said chain being bendable from an extended linear position in one direction only, a pivot hinge on said sash, said chain being connected thereto, slideable and bendable through said guide and actuated by said worm, angular slots in the links 10 of said chain for mesh with the teeth of said worm, whereby movement of said chain effects relative adjustment between the frame and sash, in relation to the specifically mentioned side of said frame, both the axis of said sash and the axis 15 of said pivot hinge being parallel to the axis of swing of said sash and the axes of the chain links being at right angles thereto, the side of said frame comprising a jamb member and a stop member, the transverse sections of the stop mem- 20 ber and the operator casing being substantially identical whereby extensions of the stop may be aligned with the operator casing and present uniplanar surfaces therewith, and a groove in the stop provides a concealing channel for the free 25 end of the chain.

10. In a structure of the kind described, a frame, a closure member therefor and movable relative thereto, an operator casing on said frame, a flexible member attached at one end to said 30 closure member and passing through said casing, operating means within said casing to impart linear motion to said flexible member relative to said casing, a curved substantially right angular guide way through said casing for said flexible 35 member, a removable stop member on said frame arranged in substantial surface alignment with said operator casing and having a groove in alignment with said guide way to form a continuation thereof to receive the portion of said flexible 40 member extending in one direction from said operator casing.

SERN MADSEN.
